J. H. VAN DORN & J. T. WHITEHOUSE.

CELL DOOR OPERATING MECHANISM.

APPLICATION FILED AUG. 18, 1913.

1,122,443.

Patented Dec. 29, 1914.

UNITED STATES PATENT OFFICE.

JAMES H. VAN DORN AND JOHN T. WHITEHOUSE, OF CLEVELAND, OHIO, ASSIGNEES TO
THE VAN DORN IRON WORKS COMPANY, OF CLEVELAND, OHIO, A CORPORATION OF
OHIO.

CELL-DOOR-OPERATING MECHANISM.

1,122,443.

Specification of Letters Patent. Patented Dec. 29, 1914.

Application filed August 18, 1913. Serial No. 785,275.

To all whom it may concern:

Be it known that we, JAMES H. VAN DORN and JOHN T. WHITEHOUSE, citizens of the United States, and residents of Cleveland, 5 in the county of Cuyahoga, and State of Ohio, have invented a certain new and useful Improvement in Cell-Door-Operating Mechanism, of which the following is a full, clear, and exact description.

10 This invention is an improvement upon the cell door controlling and operating mechanism which is shown and described in Letters Patent No. 1,007,316, granted October 31, 1911, to D. B. Van Dorn and J. T. 15 Whitehouse for prison cell door mechanism.

The primary object of this invention is to make it possible for the jailer, in the jailer's corridor, to open any door or combination of doors of a row of cells without having to 20 unlock and partially open every other door in the row.

Another object of the invention is to make it convenient for an attendant, when he puts a prisoner into one cell of a row of cells, 25 whose doors chance to be open, to shut and lock the door of that cell into which the prisoner is put.

This invention involves the use of a master bar operable from the jailer's corridor, and of bolts carried by the cell doors for engagement with said master bar, and in these respects is like the mechanism of said prior patent. But it is unlike the construction of said prior patent in that the 35 bolts, on those cell doors which are closed, are not in operative engagement with said master bar. Likewise the master bar is so constructed that it may be moved in the door opening direction so as to open all of 40 the doors which have been unlocked, without any interference from the bolts on the doors which have not been unlocked. At the same time the master bar and the bolts carried by the cell doors are so constructed 45 and arranged that the master bar may automatically engage the bolts of all unlocked doors, however much or little the doors may be opened, and thereafter simultaneously open all of the doors the full width, or simultaneously close all of the doors.

The invention consists in the construction and combination of parts by which the above mentioned characteristics of operation

are attained, and particularly in the mechanism by which to do this without affecting 55 the efficiency of the mechanism, substantially as shown in said prior patent, by which the cell door locks are released, and the cell door bolts lifted to positions such that the master bar cannot engage with them. 60

In the drawing Figure 1 is a front elevation of the upper part of the end cell of a row of cells, in which the invention is embodied, said view showing the new features in the positions they occupy when the 65 cell door is closed and locked. Fig. 2 is a front elevation of the parts which constitute the invention in the position they occupy when the said door has been unlocked. Fig. 3 is a similar view of the same parts when 70 the door locking mechanism is in the position to lock the door if the door be shut; and Fig. 4 is a sectional detail of the double acting spring and which will partially open any door when it is unlocked; and will move 75 in the closing direction any fully opened door when that door is disconnected from the master bar.

The construction shown in the drawing is like that which is shown in the prior patent 80 mentioned in many respects. Each cell door A has an upwardly extended hanger plate a, on which are the rollers a¹ (shown in dotted lines in Fig. 1), by which the door is slidably supported. A master bar F is arranged 85 to slide longitudinally adjacent to the hanger plates of all the cell doors, and it has on its top edge a notch f for each cell door. The means shown for moving this master bar are substantially like those shown in 90 said prior patent, and therefore need not be here described. Mounted on the hanger plate of each cell door is a vertically sliding bolt E, on which a roller e is mounted. This roller rests upon the top edge of the lifter 95 bar G and rides along the same as the door is opened or closed. This lifter bar is pivoted at that end toward which the door moves in opening, to a crank arm n fixed to a short rock shaft N. Near the other end 100 of the lifter bar it is provided with a downwardly extended lug g, the right hand edge of which is inclined. This end of the lifter bar rests upon a roller g¹ which is pivoted to a fixture, and in such position that as the 105 lifter bar G is moved endwise to the right,

the inclined face of the lug g will ride upon the roller and thereby lift the lifter bar, whereby also the bolt E will be lifted. Attached to the same rock shaft N is an arm 5 n^1 . To this is fixed a short flexible chain or cable K , the other end of which is secured to an endwise sliding rod K^1 . The opposite end of this rod is pivoted to an arm h , which is fixed to the upper end of 10 a vertical rock shaft H . The function of this rock shaft is substantially the same as the function of the similarly lettered rock shaft shown in said prior patent. That is to say, by rocking it the door locking mechanism may be unlocked. Any suitable door 15 locking mechanism may be employed, and it may be contained in the lock case M . Another arm h^1 secured to this rock shaft is connected by means of a cable p with an operating lever P located in the jailer's corridor.

It is to be understood that the locking mechanism, whatever may be its specific form, is such that when a door is closed it 25 will be automatically locked. To unlock it, the jailer pulls down on that lever P which is associated with said door, and thereby turns the rock shaft H , whereby the door is unlocked. The rocking of rock shaft acts 30 to move the rod K^1 , which, by pulling on cable K , rocks the rock shaft N , in a direction such that the lifter bar is moved to the right causing the inclined face of the lug g to ride up the roller g^3 , whereby bolt E is 35 lifted out of the notch f in the master bar. To the extent described there is little, if any, substantial difference between the construction shown in the accompanying drawing and that which is described in the prior 40 patent mentioned. It will be noted, however, that the walls of the notch f in the lifter bar are not of the same height,—the side f^1 which engages with the bolt E as the lifter bar is being moved to the right to 45 close the door, being considerably higher than the opposite side f^2 of the notch which engages with said bolt E when the door is being opened. Likewise this bolt E carries an adjustable tappet screw e^1 which is so 50 placed that when the door moves toward the closing position this tappet will engage the left vertical face of the lug g on the lifter bar, and will thereby move the lifter bar to the right a short distance. This distance, however, is sufficient to cause the inclined face of said lug to ride so far on the roller g^3 that the top surface of the lifter bar will be raised far enough to lift bolt E until its lower edge is in a plane which is 55 above the top edge of the door opening wall f^2 of the associated notch f . When, therefore, a cell door is closed, the bolt E associated with such cell door is directly over the associated notch f , but its lower end is 60 above the door opening side f^2 of said notch;

but is not above the door closing side f^1 thereof. If this construction be employed in connection with each door of a row of cells, it is quite apparent that the jailer can unlock 70 as many cell doors as he chooses by manipulating the appropriate levers P . As he does this, the associated lifter bar for each door will be moved to the position shown in Fig. 2 of the drawing, and thereby the bolt E will be raised until its lower end is above 75 the door closing side f^1 of the associated notch f . When the described parts have been moved to this position it will be understood that the rock shaft H has been so rocked as to unlock the door. Thereupon a 80 spring plunger R , carried by the door, reacting against a fixed bracket T , will open the door slightly, thereby carrying the bolt E to the left of the associated notch f . When this has been done the lever P , by which 85 these results have been accomplished should be restored to the door locking position. When this has been done, the lifter bar G and the bolt E will take the position shown in Fig. 3 of the drawing. When, now, the 90 master bar F is moved in the door opening direction, the inclined face thereon adjacent to the notch will move the bolt E upward, and said bolt will drop into the notch f so that by the further movement of the master 95 bar F this door and all other doors in like condition may be opened wide. It is to be observed, however, that the bolts E which are associated with every cell door which was allowed to remain locked will be in the 100 position shown in Fig. 1 when the leftward movement of the master bar begins; and this permits the associated notched part of the master bar to pass beneath said bolt, as said master bar moves in the door opening direction. 105

The spring plunger R above mentioned is a double acting affair which is normally held in a neutral position by oppositely acting springs r , r^1 . Both ends of the plunger project from the supporting bracket a^1 . When a cell door has been fully opened, its spring plunger R will have engaged a fixed bracket T^1 ; whereby spring r^1 will be put under tension. If, when a cell door is open, the 110 jailer in the jailer's corridor, by operating the proper lever P , lift the bolt E of that door out of engagement with the master bar, the spring plunger R will move the now freed door in the closing direction far 115 enough to carry bolt E away from the notch f . The jailer should now move the lever P back to the normal position. This will cause the bolt E to be lowered so that when the master bar is moved in the door closing 120 direction, it will automatically engage said bolt. But before the master bar is so moved, a jailer in the prisoners' corridor, i. e. at the cell door, can close said door. And when the 125 door is closed it will be automatically locked, 130

as, for example, by the mechanism provided for that purpose, as shown in the prior patent mentioned.

Having described our invention, we claim:

5 1. In cell door operating mechanism, the combination of a sliding cell door, a movable bar having a notch, and beveled surfaces on both sides of the notch leading thereto, a vertically movable bolt carried by 10 said door and adapted to engage said notch, means operable from a distance for lifting said bolt, and means which are operated by the closing of the door for lifting said bolt.

15 2. In cell door operating mechanism, the combination of a sliding cell door, a sliding master bar having a notch whose wall on the door closing side is higher than the wall on the door opening side, a vertically sliding bolt carried by the door for engagement 20 in said notch, means for lifting the bolt above the lower wall of said notch when the door is closed, and means operable from a distance for lifting the bolt above the higher wall of said notch at will.

25 3. In cell door operating mechanism, the combination of a sliding cell door, a movable master bar having a notch whose door closing side is higher than its door opening side, a vertically movable bolt carried by 30 the door and adapted to engage in said notch, means operable from a distance for lifting the said bolt above the highest wall of said notch, and means which are caused to operate by the closing of said door to lift 35 said bolt above the door opening side of said notch.

40 4. In cell door operating mechanism, the combination of a sliding cell door, a movable master bar having a notch whose door closing side is higher than its door opening side, a vertically movable bolt carried by the door 45 and adapted to engage in said notch, means operable from a distance for lifting the said bolt above the highest wall of said notch, a lifter bar on which the bolt rides as the cell door opens and closes, which lifter bar has a depending lug which is inclined on one 50 face, a supporting device on which said inclined face of the lug will ride as the lifter bar is moved endwise whereby the lifter bar

will likewise be raised, and a tappet carried by the door which will engage said lifter bar and move it endwise as the door is closed.

5 5. In cell door operating mechanism, the combination of a cell door, a sliding master 55 bar having a notch whose door closing side is higher than its door opening side, a vertically movable bolt carried by the door and adapted to engage said notch, a lifter bar on which said bolt rides as the cell door is 60 opened and closed, means whereby the endwise movement of the lifter bar will cause it to move upward, door locking mechanism, door unlocking mechanism operable from a distant station, and connections between 65 said door unlocking mechanism and said lifter bar, which connections include a flexible member, and a tappet carried by the door and adapted to engage said lifter bar and move it endwise as the door is closed. 70

6. In cell door operating mechanism, the combination of a sliding cell door, two fixed brackets, and spring actuated mechanism carried by said door and adapted to engage with and to be put under tension by said 75 brackets respectively when the door is opened and when it is closed, a master bar operable from a distant station and having a bolt notch, a bolt carried by the door for engaging said notch, and means operable 80 from a distance for disengaging the bolt from the door opening side of said notch.

7. In cell door operating mechanism, the combination of a sliding cell door, a movable bar having a notch and beveled surface 85 on both sides of the notch leading thereto, a vertical movable bolt carried by said door and adapted to engage said notch, and means which are operated by the closing of the door for lifting said bolt above the door opening 90 side of said notch.

In testimony whereof, we hereunto affix our signatures in the presence of two witnesses.
